UNITED STATES PATENT OFFICE.

CATHERINE O'HARA, OF NEW YORK, N. Y., ASSIGNOR TO THE BUTTERICK PUBLISHING CO., (LIMITED,) OF SAME PLACE.

DESIGN FOR A CHILD'S COSTUME.

SPECIFICATION forming part of Design No. 14,366, dated October 23, 1883.

Application filed August 23, 1883. Term of patent 3½ years.

To all whom it may concern:

Be it known that I, CATHERINE O'HARA, of the city, county, and State of New York, have invented and produced a new and original Design for a Pattern of a Child's Costume, (numbered 8,845;) and I do hereby declare that the engraved prints accompanying this specification convey to any one accustomed to using paper patterns a clear understanding 5 of how a garment made up by the pattern will appear.

The design combines a center front partly covered by a full-vest section, slightly fitted side fronts, a back box-plaited to a yoke top,

and Shirred below the waist-line, and belt-sections extending from the shirrs and lapped at the left side of the front, coat sleeves being added.

What I claim as my invention, and desire to secure by Letters Patent, is—

The design for a child's costume, as shown in the engraved prints accompanying this specification.

CATHERINE O'HARA.
